NOZZLE

Jordan W. Grant, Portsmouth, Va.

Application November 15, 1938, Serial No. 240,577

2 Claims. (Cl. 299—57)

The device forming the subject matter of this application is of the type shown in my former Patent No. 1,852,926, issued on April 5, 1932.

Although the article shown in the patent above referred to has been very satisfactory in practical operation, it has been found, with the passage of the years, that improvements can be made in the nozzle or outlet member, and its mounting, and the improved structure will be made manifest as the description proceeds.

In the accompanying drawings:

Fig. 1 shows, in vertical section, a device constructed in accordance with the invention;

Fig. 2 is a section taken approximately on the line 2—2 of Fig. 1.

The device forming the subject matter of this application preferably is made of metal, and, for the purpose of defining relative locations of parts, the front end of the device is marked by the letter A, the rear end of the device being marked by the letter B.

A hollow body 1 is provided, and includes an upstanding neck 2, the axis of which is rearwardly inclined with respect to the vertical, as Fig. 1 of the drawings will indicate. An integral boss 3 is carried by the substantially-horizontal bottom of the body 1, and is disposed in the axis of the neck 2. A base plate 4 extends beneath the rear end of the body 1, the base plate being attached to the bottom of the body by any desired number of securing elements 5. The base plate 4 has an upwardly extended flange 6, secured to the rear portion of the neck 2 by an attaching element 7. Any desired number of pointed feet 8 are carried by the base plate 4 and by the bottom of the body 1, and serve as supports for the article.

A deflector 9 is located in the neck 2 and rests upon the bottom of the body 1, the deflector having a rearwardly extended lug 10, abutting against the rear wall of the neck 2. The attaching element 7 enters the lug 10 and serves to hold the deflector 9 in place. The deflector 9 is spaced from the inner surface of the neck 2 by the lug 10. The deflector 9 is supplied with a notch 11, receiving the boss 3 on the bottom of the body 1. The deflector 9 is concaved vertically and rearwardly, as shown at 12, and the deflector is concaved or curved in a direction at right angles to the axis of the boss 3. The upper edge of the deflector 9, marked by the numeral 14, is located slightly below the upper edge of the neck 2. The forward edges 15 of the deflector 9 are oppositely disposed, and are located in a plane passing through the axis of the boss 3.

The water proceeding through the device, in the direction of the arrow C in Fig. 1, is received by the deflector 9, and is directed upwardly, in a direction parallel to the axis of the neck 2. A smooth and even flow in the water is produced, there is no hammer or jar, pump-energy is conserved, velocity is increased, and the volume of water discharged is increased also, all due to the provision of the deflector 9, located and constructed as described, and as shown in the drawings.

The forward portion of the hollow body 1 is supplied with a plurality of inlet necks 16, the axes of which converge rearwardly and toward the neck 2. Forwardly-closing check valves 17 are disposed in the inlet necks 16.

The lower end of a rearwardly inclined post 39 is mounted in the boss 3 on the bottom of the body 1. A loop-shaped outlet member 40 (Fig. 2) is mounted to turn on the fixed post 39. The construction of the outlet member 40 will be taken up hereinafter. The outlet member 40 includes a hollow transverse part 41, best disclosed in Fig. 2 and mounted to turn on the upper part of the post 39. The forward part 41 of the outlet member 40 includes a depending sleeve 42 (Fig. 1) mounted to turn within the neck 2 of the body 1, between a portion of the neck and the upper part of the deflector 9.

The outlet member 40, hereinbefore referred to only in connection with the part 41 thereof, includes oppositely disposed U-shaped parts 56. The rear parts 56 of the outlet member 40 are supplied at their front ends with outstanding flanges 57, cooperating with corresponding flanges 58 on the ends of the forward part 41 of the outlet member 40, the flanges 57 and 58 being held together by removable securing elements 59, such as bolts. By removing the bolts 59, the rear parts 56 of the outlet member 40 may be detached from the part 41 of the outlet member, and it is then possible to remove, and renew, packings 60, to be alluded to hereinafter, and carried by the rear, inner ends of the parts 56. The separable construction shown at 57—58—59 is useful, also, in facilitating the renewal of many portions of the structure, to be described hereinafter.

The numeral 61 marks a nozzle, located in the median vertical plane of the device. The nozzle 61 has outwardly extended branches 62, the ends of the branches 62 being received for rotation in the inner ends of the parts 56 of the outlet member 40, the construction being such that the nozzle 61 can be swung up and down, 55

between the solid line and dotted line positions of Fig. 1.

The inner ends of the parts 56 of the outlet member 40, and the terminal portions of the branches 62 of the nozzle 61, are supplied with cooperating recesses 63, wherein is mounted the packing 60, hereinbefore referred to. The packing 60 is of annular form, and is sustained in its annular form by a perforated metal ring 64, located within the packing and received in the cooperating recesses 63, as Fig. 2 will show. A nipple 65 is mounted in each inner end portion of the parts 56 of the outlet member 40. The bore of the nipple 65 communicates with a duct 66 in the inner end of the member 56, and leading to the cooperating recesses 63.

Noting Fig. 2 of the drawings, it will be seen that the passages afforded in the parts 41 and 56 of the outlet member 40 are of greatest cross sectional area adjacent to the sleeve 42 of Fig. 1. Thence, they taper gradually and fairly, to the place where the branches 62 of the nozzle 61 merge into the outlet member of the nozzle. The gradual taper of the passages through the outlet member 41 and the branches 62 of the nozzle tends to reduce friction and resistance to the passage of water to the nozzle 61, and the volume of water discharged is increased, velocity being increased also. It may be noted here, incidentally, that the side portions of the outlet member 40 extend outwardly to such an extent that they form convenient handles for carrying the device about.

It can be ascertained from Fig. 1 that the outlet member 40 slopes backwardly and downwardly somewhat sharply. The back-kick of the water passing through the nozzle 61 thus is brought low, and increased stability results, there being a decreased tendency to tip the article over, due to the back-kick of the passing water. This consideration is especially valuable if the nozzle 61 happens to be so disposed that it is discharging at an angle that, otherwise, would tend to produce the undesirable result referred to.

Comparing Figs. 1 and 2, where the forward walls of the branches 62 of the nozzle 61 join, there is located an integral segment 67, extended into an opening 68 within the contour of the outlet member 40, the segment being supplied (Fig. 1), with a projection or stop 69 at one end. The segment 67 is engaged by a worm 70 on a shaft 71, the shaft being journaled in brackets 72 on the part 41 of the outlet member 40, the shaft being held against longitudinal movement by collars and pins 73, or any equivalent struc-

tures. A crank 74 (or something else) on the upper end of the shaft 71, constitutes means whereby the shaft may be rotated. Noting Fig. 2, it will be observed that the opening 68 that extends vertically through the outlet member 40, affords room for the segment 67, the worm 70, the shaft 71, and the brackets 72. The stop 69 on the segment 67 (Fig. 1) is adapted to co-operate with the lower end of the worm 70 on the shaft 71, and, thus, the downward swinging movement of the nozzle 61 is limited to the dotted line position of Fig. 1.

The advantages of the device are found mostly in its structural features, and have been set forth in the foregoing description. They need not be repeated at this place.

As to general operation, the water enters by way of the inlets 16 and leaves by way of the nozzle 61, the nozzle being adjusted to different angles by the simple train of parts including the shaft 71, the worm 70 and the segment 67.

The inlets 16 afford a means whereby several pieces of hose may be made to discharge into the body 1. If any piece of hose is removed, the valve 29 of Fig. 1 closes automatically, and is held closed by the back pressure within the body 1, created by water delivered through the pieces of hose which remain assembled with the body.

Having thus described the invention, what is claimed is:

1. In a device of the class described, a body having an inlet, a loop-shaped outlet member, the forward portion of which is intermediately connected to the body, in communicating relation therewith, a nozzle having oppositely disposed lateral branches rotatably mounted in the rear portions of the outlet member, the branches and the rear portion of the outlet member having internal, communicating recesses, an annular packing in the recesses, an annular sustaining ring on the packing, and a fixed nipple having a bore discharging into the recesses.

2. In a device of the class described, a hollow body having an inlet, and provided on its bottom with an upstanding boss, a nozzle-part mounted on the body, a post attaching the nozzle-part to the body and assembled with the boss, there being a passage through the body and through the nozzle-part, the passage making a turn within the body, between the inlet and the nozzle part, a curved deflector renewably mounted in the body at said turn, and having a notch receiving the boss, and means for attaching the deflector detachably to the body.

JORDAN W. GRANT.
